UNITED STATES PATENT OFFICE.

ALFRED ERNEST WALLER, OF BRONXVILLE, NEW YORK, ASSIGNOR TO WARD LEONARD ELECTRIC COMPANY, A CORPORATION OF NEW YORK.

RHEOSTAT.

Application filed December 31, 1920. Serial No. 434,278.

To all whom it may concern:

Be it known that I, ALFRED E. WALLER, a citizen of the United States, residing at Bronxville, in the county of Westchester and State of New York, have invented certain new and useful Improvements in Rheostats, of which the following is a specification.

My invention is particularly well adapted for the type of rheostats controlling comparatively large currents of low voltage, such as in rheostats for electroplating and other purposes.

One object of my invention is to produce a rheostat of the above type which will be of comparatively large capacity and small size; another object is to produce a rugged and durable construction; and another object is to produce a simple form of construction economical in manufacture by reason of its simplicity and comparatively small amount of metal required in the contact making and breaking parts. Another object is to secure ample heat radiating capacity.

One object of my improvement is to produce not only a small sized conveniently operated rheostatic contact device, but also one which will insure a firm contact over a comparatively large surface area and be rugged in construction. My improved contact means is a rotary device and compared with the usual knife-blade switch is superior in insuring firm and adequate contact, is self-aligning and self-cleaning and comparatively slight pressure will close the rheostat contacts and will subject the contact surfaces to a high pressure insuring intimate contact between the surfaces with precision and certainty. Knife switches are easily bent which causes improper and poor contact of the parts; and when they have been used and become slightly worn, the contact surfaces do not engage well, with the consequent poor contact and overheating. The knife switch also requires more metal in its construction than is the case with my improved switch. These objects and advantages of my invention, as well as other advantageous features, will be understood from the following description and accompanying drawings which illustrate a preferred embodiment of my invention.

Fig. 1 is a front elevation; Fig. 2 is a side

view, and Fig. 3 is a vertical cross section 55 of one of the switches.

The rheostat comprises two panels 1, 1^a in the form of plates of insulating material, the panels being supported in any suitable manner such as by the iron strips or frame 60 pieces 2. On the upper panel is illustrated a controlling switch 3, a volt meter 4 and ammeter 5, as is usual in electroplating apparatus.

The lower panel 1^a supports the resistance units 6, which in this instance are in the form of tubular units having a tube of insulating material upon which are wound the resistance wires of suitable size and length and material to give the resistance required 70 for the particular case. The resistance wires are coated and embedded in insulating material for protection, such as vitreous enamel. These resistance units will be of different sizes and of different resistance values so as to give the variation and range of control desired. They are supported endwise on the panel 1^a by screws 7 which pass through the panel and through the resistance tubes respectively and have a nut and washer 7^a at their rear ends for clamping the tubes in position, as shown in Fig. 2. On the face of the lower panel 1^a and extending horizontally along the upper portion thereof is a heavy metal bar 8 of brass 85 or other suitable material. It has a number of circular holes through which pass forwardly from the rear, with a suitable amount of clearance space, the screw bolts or studs 9. On the front end of each screw 90 or screw bolt 9 is a nut or collar 10 having a single wing 10^a. The pitch of the thread of the screws 9 is quite high so that a half turn of the nut 10 will cause considerable axial movement of the nut. When the wing 10^a is turned upwardly to the position shown by the left-hand nut in Fig. 1 and as also shown in Fig. 3, the nut is brought into firm contact with the bar 8 making electrical connection between the screw 9 and the bar 8 over a large contact area and with a high degree of pressure, even with comparatively small pressure by the operator on the wing 10^a. Turning the wing 10^a to the left and letting it fall to its lower position breaks 100 the contact between the nut and the plate 8 and causes the nut to move rapidly away from the plate to a considerable distance in

about a half revolution of the nut. Stop pins 11 are mounted on the panel 1^a below the switches respectively and are engaged by the wings 10^a to prevent them from 5 turning beyond a certain limit.

Secured to the back of the panel 1^a and extending horizontally along the upper portion, is a strip of insulating material 1^b. Each screw 9 has a rear portion which passes 10 through the strip 1^b and also has a collar or shoulder 9^a which engages the inner face of the strip 1^b. Nuts 9^b on the rear threaded portion of the bolt 9 securely clamp the bolt 9 to the strip 1^b.

Extending horizontally along the lower portion of panel 1^a and at the back of the panel, is a metal strip 12. At the left-hand end of this strip and extending through it and through the panel 1^a is a terminal connection 12^a, consisting of a bolt and nuts and washers which serves as one of the main terminals of the apparatus. At the right of the panel is another terminal 13, which consists of a bolt, nuts and washers and is 20 mounted on the panel and forms the other main terminal of the apparatus. From the main terminal 13 a heavy conductor extends, at the rear of the panel, to and is electrically connected with the metal strip 8 by means 25 of screw bolts 14. These screw bolts have their heads engaging the face of the metal strip 8 and have nuts at their rear ends which serve to engage the conductor from the terminal 13 and also serve to clamp 30 the metal strip 8 and the insulating strip 1^b in position on panel 1^a.

One of the leads from each of the resistance units 6 is electrically connected to the metal strip 12 at the back of the panel by 40 means of screw bolts 15. These screw bolts extend through the panel 1^a and the strip 12, having their heads engaging the face of the panel, while the nuts and washers at the rear of the screw bolts serve to receive 45 the leads from the resistance units and also serve to clamp the strip 12 to the panel. The other leads from each of the resistance units 6 are connected respectively to the screw bolts 9 by being clamped between the 50 nuts 9^b. In some cases the terminals from two or more of the resistance units may be connected to one of the screw bolts 9 and thus may be grouped to give the desired steps of control according to the requirements of each particular case.

In operation and when the wings 10^a are swung to their lower position, the circuit through the resistance units is open. The swinging of any wing 10^a to its upper position as for example, the left-hand one of 60 Fig. 1 causes the circuit between its screw 9 and the plate 8 to be closed, as above explained, and so places one or more resistance units connected thereto in the main circuit. If it be desired to increase the cur-

rent, another one or more of the wing nuts are rotated to close the particular resistance circuit or circuits desired to give the proper amount of current. It will be understood that the resistance units are of various sizes and resistances and are graduated so that a very large range of current control is secured by closing any one of the wing nuts and by closing more than one of the wing nuts in different combinations and 75 groupings as desired.

It will be seen that the construction is very rugged and durable and conveniently manufactured and assembled. It is also a simple form of construction and secures a 80 large range of control with comparatively few switches.

The form of switch is one which is certain to give a firm and adequate contact under high pressure. The circuit can be closed very quickly by rapidly turning the wing nut and it is opened quickly, because when the operator forces the wing nut to open the switch, the contact pressure suddenly releases and by reason of the high pitch of the thread, the nut moves a considerable distance with a small angular movement. In order to secure a large pitch of the thread on the front end of the screw bolts 9, a double or treble thread may be used and thus secure ample contact and strength between the wing nut and the screw bolt. In this particular instance a double thread is used. The stops 11 prevent the wings of the nuts from turning beyond 90 their lower position, which prevents the nuts from being taken off the screw bolts and from being misplaced or lost. The construction is preferably made so that the closed position of the nut brings the wing 10^a to its upper position. This arrangement limits the rotation of the wing nut to about 180° at one side of the nut only and prevents any interference or engagement of the wing of one nut with the wing of the adjacent nut. It thus permits the nuts to be located near together, it only being necessary to have 105 sufficient clearance between the wing of one nut and its adjacent nut at the left. It thus gives a more compact construction, as without the above construction, the nuts would have to be placed far enough apart to give 110 clearance between the wings of two adjacent nuts when extending toward each other.

My invention may be embodied in various modified forms of construction and the parts variously related without departing from the scope thereof.

I claim:—

1. A rheostat comprising resistance elements, a conducting element, a plurality of threaded elements insulated from said conducting element, and a plurality of rotatable elements on said threaded elements respectively for connecting and disconnecting 125

130

- said threaded elements with said conducting element and thereby connecting and disconnecting said resistance elements in circuit. 2. A rheostat comprising a plurality of 5 resistance elements connected to a terminal, a conducting element, a plurality of threaded elements extending through but electrically insulated from said conducting element, said resistance elements being connected respectively to said threaded elements, and rotatable elements on said threaded elements for connecting said threaded elements respectively with said conducting element. 10 15 3. A rheostat comprising a panel, a conducting element on the face of said panel, threaded elements mounted on said panel and extending through said conducting element and insulated therefrom, resistance 20 elements located on the rear of said panel and connected to said threaded elements at the rear of said panel, and rotatable elements on said threaded elements respectively in front of said conducting element 25 for connecting and disconnecting said resistance elements with said conducting element. 4. A rheostat comprising a panel, a perforated conducting element on the face of said panel, threaded elements projecting 30 forwardly through said perforations, resistance elements connected to said threaded elements, and rotatable elements on said threaded elements in front of said conducting element for connecting and disconnecting said threaded elements respectively to 35 said conducting element. 5. A rheostat comprising a panel, a perforated conducting element on the face of said panel, threaded elements projecting 40 forwardly through said perforations, resistance elements connected to said threaded elements, and rotatable elements on said threaded elements in front of said conducting element for connecting and disconnecting said threaded elements respectively to 45 said conducting element, said threaded elements having a high pitch. 6. A rheostat comprising a panel, a perforated conducting element on the face of 50 said panel, threaded elements projecting forwardly through said perforations, resistance elements connected to said threaded elements, and rotatable elements on said threaded elements in front of said conducting element for connecting and disconnecting said threaded elements respectively to said conducting element, and stops mounted on said panel for limiting the rotation of said rotatable elements. 55 60 7. A rheostat comprising a panel, a perforated conducting element on the face of said panel, threaded elements projecting forwardly through said perforations, resistance elements connected to said threaded elements, and rotatable elements on said 65 panel for connecting and disconnecting said threaded elements in front of said conducting element for connecting and disconnecting said threaded elements respectively to said conducting element, said rotatable elements having projecting handles. 70 75 8. A rheostat comprising a panel, a perforated conducting element on the face of said panel, threaded elements projecting forwardly through said perforations, resistance elements connected to said threaded elements, and rotatable elements on said threaded elements in front of said conducting element for connecting and disconnecting said threaded elements respectively to said conducting element, said rotatable elements having projecting handles, and stops mounted on said panel for limiting the rotation of said rotatable elements when said handles are in their lower position. 80 85 9. A rheostat comprising a panel, a plurality of resistance units mounted on the rear of said panel, a perforated conducting element mounted on the face of said panel, a plurality of threaded elements projecting through said perforations respectively, and a plurality of rotatable elements on said threaded elements respectively for connecting and disconnecting said threaded elements with said conducting element, said resistance units being connected to said 90 threaded elements respectively. 95 10. A rheostat comprising a panel, a plurality of tubular resistance units mounted endwise on the rear of said panel, a perforated conducting element mounted on the face of said panel, a plurality of threaded elements projecting through said perforations respectively, and a plurality of rotatable elements on said threaded elements respectively for connecting and disconnecting said threaded elements with said conducting element, said resistance units being connected to said 100 threaded elements respectively. 105 11. A rheostat comprising a panel, a conducting element on the face of said panel, a second conducting element on said panel, a plurality of resistance elements mounted on said panel between said two elements, threaded elements extending through said first named conducting element but insulated therefrom, and rotatable elements on said threaded elements for connecting and disconnecting them respectively with said first named conducting element, said resistance elements being electrically connected between said second named conducting element and said threaded elements respectively. 110 115 12. A rheostat comprising a conducting element, a resistance element, a second conducting element insulating from said first named conducting element, said resistance element being connected to said conducting elements respectively, and a coupling device for connecting said conducting elements, said device comprising a stud and a rotat- 120 125 130

- able collar on said stud, the said collar and stud having an inclined surface engagement.
13. A rheostat comprising a plurality of resistance elements, a conducting element, ⁵ said resistance elements being connected to said conducting element, a plurality of conducting elements to which said resistance elements are respectively connected, and a plurality of separately operable coupling ¹⁰ devices for electrically connecting said conducting elements respectively with said conducting element, each of said devices comprising a stud and a rotatable collar on said stud, the said collar and stud having an inclined surface engagement.
- ¹⁵ 14. A rheostat comprising a plurality of resistance elements, a conducting element, said resistance elements being connected to said conducting element, a plurality of conducting elements to which said resistance elements are respectively connected, and a plurality of separately operable coupling devices for electrically connecting said conducting elements respectively with said conducting element, each of said devices comprising a stud and a rotatable collar on said stud, the said collar and stud having an inclined surface engagement and having a high pitch. ²⁰ ²⁵

ALFRED ERNEST WALLER.
